UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.
STAY-BOLT STRUCTURE.

1,295,861.

Specification of Letters Patent.

Patented Mar. 4, 1919.

Application filed April 26, 1918. Serial No. 230,896.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as will enable others skilled in the art to which it appertains to make and use the same.

This invention relates to improvements in staybolt structures for boilers,—the object of the invention being to provide simple and efficient means whereby the cap or closure of the bearing sleeve of a flexible staybolt structure may be quickly removed to permit inspection and testing of the bolt, and then quickly replaced.

With this and other objects in view, the invention consists in certain novel features of construction and combinations of parts as hereinafter set forth and pointed out in the claims.

In the accompanying drawings; Figure 1 is a view in section showing an embodiment of my invention; Fig. 2 is a view in elevation; Figs. 3 and 4 are views illustrating the manner of assembling the parts; Fig. 5 is a plan view of the cap or closure, and Fig. 6 is a sectional view of the cap or closure and showing a slight modification.

1 represents a bearing sleeve threaded externally to screw into a boiler sheet, and to facilitate the application of said sleeve to the boiler sheet, it may be provided with an angular portion 3 to receive a wrench. The sleeve 1 is provided interiorly with a curved bearing face 4 to receive the curved or spherical head 5 of a staybolt 6.

The bearing sleeve 1 is made with an integral extension 7, preferably having a larger bore than that portion of the sleeve in which the head of the bolt has its bearing, and said sleeve extension is provided in its wall with diametrically opposite elongated slots 8,—each of which is diagonally disposed or inclined so as to form cam slots. Near one end of each of the cam slots, the inner face of the wall of the sleeve extension is recessed, so as to form longitudinal grooves or recesses 9 for a purpose hereinafter explained.

A removable cap or closure 10 is disposed within the sleeve extension 7 and normally

bears against a seat 11,—said cap having a 55 general hemispherical form for the accommodation of the spherical head of the bolt but the concavity of said cap is of sufficient dimensions to provide a space 12 which will permit slight endwise displacement of the 60 staybolt.

The cap or closure 10 is provided at diametrically opposite points with laterally projecting lugs 13—13 which, when the said cap is placed within or removed from the sleeve 65 extension, will pass through the longitudinal recesses 9 and then, when the cap is turned, said lugs will move through the slots 8 and engaging the cam walls of said slots, will cause the cap to be tightly clamped to its 70 seat.

In order to facilitate the turning of the cap, the same may be provided with an angular head 14 to receive a wrench, and, if desired, the lugs 13 may be provided with 75 sockets 15 to receive a spanner wrench, as indicated in Fig. 6.

When it is desired to expose the head of the bolt for inspection and to test the bolt, the operator will first turn the cap or closure 80 10 so as to unlock the same from its seat and then remove said cap from the sleeve,—such removal being permitted by the alinement of the lugs 13 with the grooves or recess 9 in the wall of the sleeve extension. It is apparent that by reversing these operations, the cap or closure may be quickly replaced and locked.

Having fully described my invention what I claim as new and desire to secure by Letters-Patent, is:—

1. In a staybolt structure, the combination with a bearing sleeve having cam slots, of a removable cap or closure adapted to be seated in said sleeve and having lugs to enter said cam slots.

2. In a staybolt structure, the combination with a bearing sleeve having an extension provided with cam slots, of a removable cap in said sleeve extension and having lateral lugs to enter said cam slots, said sleeve extension having interior recesses for the passage of said lugs when the cap is being removed from or inserted into said sleeve extension.

3. In a staybolt structure, the combination with a bearing sleeve having a cap seat therein and having cam slots in its wall, of a removable cap to enter said sleeve and rest

on said seat, said cap having lugs to enter said cam slots and the sleeve having interior recesses for the passage of said lugs, and means permitting the application of a wrench 5 to said cap for turning said cap to lock or unlock the same.

In testimony whereof, I have signed this

specification in the presence of two subscribing witnesses.

ETHAN I. DODDS.
